UNITED STATES PATENT OFFICE.

PAUL BOMMARITO, OF DETROIT, MICHIGAN.

COMPOSITION FOR THE TREATMENT OF GOITER.

No Drawing.

Application filed May 4, 1925. Serial No. 28,019.

To all whom it may concern:

Be it known that I, PAUL BOMMARITO, a citizen of the United States, residing at Detroit, in the county of Wayne and State of

Michigan, have invented a new and useful Improvement in a Composition for the Treatment of Goiter, of which the following is a specification.

My invention relates to a composition, which is particularly adaptable for use in the treatment of goiter. In medical science, goiter is considered to be a pathological enlargement of the thyroid gland, in which the biological cells of this gland are abnormal to such an extent that the physiological internal secretion of the thyroid gland in the last stages of the goiter is prevented, and in all stages, the internal secretion of the thyroid gland is disturbed.

It is recognized that a treatment which will revive the internal secretion of the gland, will serve to restore the biological cells to normal condition, decrease the enlargement, and remove the pathological disturbance.

The decrease of the enlargement and the removal of the pathological disturbance will be effected by the revival of the normal flow of the internal secretion of the gland, but the treatment which will revive the internal secretion, will also directly aid the restoration of the biological cells to normal condition.

To provide a composition which will produce the desired effect, is an object of the present invention.

In the composition, the ingredients used are: Elementary iodine, potassium iodide, guaiacol, distilled water, and glycerine.

The fundamental ingredients which are designed to affect the biological cells of the thyroid gland in the manner indicated, and remove the pathological disturbance are: elementary iodine, potassium iodide, and guaiacol.

The distilled water serves as a vehicle for the fundamental ingredients and as a solvent. The glycerine also serves as a solvent, and tends to reduce irritation incident to the injection of the composition and controls, to some extent, the reaction resulting from the injection.

In this description, the elementary iodine referred to is the pure iodine in crystal state.

These ingredients are preferably used in the following proportions, to wit: elemen-

tary iodine, twenty centigrams; potassium iodide, two grams; guaiacol, four grams; distilled water, fifteen grams; pure neutral glycerine, ten grams.

It will be noted that the glycerine is set out as being pure and neutral.

The composition is administered by intra-muscular injections and on this account, the solvent must be free from any qualities which would unduly irritate, or infect the person receiving the treatment. The amount of the mixture which will be injected and the periods of time at which the injection is to be made, will be determined largely by the skill of the doctor administering the treatment, and the condition and constitution of the patient.

The potassium iodide serves to assist the dissolving of the elementary iodine.

Whether or not there is any chemical reaction between the ingredients used, the applicant is at present unable to state. The statement is made, however, that the ingredients used have given very satisfactory results in the treatment of cases of goiter, in various degrees of development, and the composition set out herein is the result of long and frequent experiments, so that the applicant is convinced that the three fundamental ingredients used are essential and that they have a co-operative relation in their effect on the patient treated. This conviction has arisen from the studied results in many experiments in which one of the fundamentals was omitted and the other two combined. The experiments were also carried further in combining two of the fundamental ingredients set out herein with other ingredients, the result being that the composition set out herein was discovered to be a most efficient treatment to which the ailment promptly responds.

The amounts of the ingredients set out are the amounts which have been discovered to be the most effective, although it will readily appear to those skilled in the practice of medicine, that slight variations in the proportionate amounts might be had without diminishing, to any great extent, the benefits derived from the use of the composition.

What I claim is:

1. A composition for intra-muscular treatment of goiter, comprising: elementary iodine, potassium iodide, guaiacol, in solution in a vehicle suitable for intra-muscular injection.

2. A composition for intra-muscular treatment of goiter, comprising the following ingredients in substantially the proportions set out, to wit: elementary iodine, twenty centigrams; potassium iodide, two grams; guaiacol, four grams; and a vehicle suitable for intra-muscular injection.
5. A composition for intra-muscular treatment of goiter comprising in substantially

the proportions set out the following ingredients, to wit: elementary iodine, twenty centigrams; potassium iodide, two grams; guaiacol, four grams; and a vehicle suitable for intra-muscular injection.

In testimony whereof, I have signed the foregoing specification.

PAUL BOMMARITO
